CHARLES STEIN, OF PHILADELPHIA, PENNSYLVANIA.

Letters Patent No. 75,313, dated March 10, 1868.

IMPROVEMENT IN FLUID-METERS.

The Schedule referred to in these Letters Patent and making part of the same.

TO ALL WHOM IT MAY CONCERN:

Be it known that I, CHARLES STEIN, of Philadelphia, Pennsylvania, have invented a Mode of Registering the Flow of Fluids; and I do hereby declare the following to be a full, clear, and exact description of the same.

My invention consists of a rotating or oscillating-magnet and a registering-bar, operated by the same, as fully described hereafter, in combination with any fluid-meter, for the purpose of registering the flow of the fluid contained therein.

In order to enable others skilled in the art to make and use my invention, I will now proceed to describe its construction and operation, reference being had to the accompanying drawing, which forms a part of this specification, and in which—

Figure 1 is a plan view partly in section, representing one modification of my device for registering the flow of fluids.

Figure 2, a sectional elevation of the same.

Figures 3 and 4, modifications of my invention; and

Figure 5, a plan view of fig. 4.

A is a circular metallic box, secured to and forming a part of the base-plate, B, and covered at the top, so as to be perfectly air-tight, by a screw-lid, C, the latter being strengthened by a rigid metal bar, a, extending across it, and having on each side of this bar a glass cover, b, through which the interior of the box may be observed. Communicating with the inside of the vessel, A, and directly opposite one another, are inlet and outlet-branches D and D', and a portion of one side of the said vessel is cut away and has inserted in it a thin plate, c, of copper, or of any suitable conducting metal. The trunnions of a vertical spindle, E, turn in a step, d, at the centre of the base-plate, and in a set-screw, f, in the lid of the box A, the pressure upon the spindle being so regulated by the latter as to cause the least possible amount of friction, and the said spindle is prevented from turning in any direction except that indicated by the arrow, by a pawl and ratchet, g, as shown in fig. 2. A disk, F, is secured to the spindle E at a point about midway between the top and bottom of the box A, and to this disk is secured a magnet, G, the opposite poles h and h' of which are at right angles to each other, and are each provided, near to their outer ends, with a hollow metal sphere, i. A bent metal bar, H, having spheres i', is also secured to the disk F, for the purpose of balancing the magnet and its spheres when the spindle is turned. A registering-bar or lever, J, of magnetized steel or soft iron, is delicately hung to a projection, k, on the base-plate, without the vessel A, and in such a position that one of its arms may be brought in contact with the copper conducting-plate c of the said vessel.

The operation of this instrument is as follows: The water or other liquid to be measured passes into the vessel A, through the inlet-branch D, and out through the branch D', and in its passage strikes the spheres i and i', thus causing the spindle and magnet to revolve at a greater or less speed, according to the velocity of the fluid. The outer ends of the magnet, in revolving, are almost in contact with the sides of the vessel A; and as its opposite poles pass the copper conducting-plate and registering-bar J, the latter is alternately attracted and repelled by them and caused to vibrate. This movement of the bar is communicated by its opposite arm to a train of registering-wheels and pointers, such as are used in ordinary gas-meters.

In the modification of my invention shown in fig. 3, a copper lid or cover, C, is bolted to the box A, and an ordinary horse-shoe magnet, G, is secured vertically to the spindle, in such a position that its opposite poles are almost in contact with the copper plate. This magnet is also provided with hollow spheres, and is operated in the same manner as the preceding one, by the liquid passing through the box. The registering-bar J is, in this case, hung to a stem projecting above the copper plate C, and its outer ends are bent downwards, so as to nearly touch the latter. The bar J is attached by and follows the motions of the inside magnet as it revolves, and is in any suitable manner connected with a train of wheel-work, by means of which the number of revolutions are registered.

Another modification of my invention, in which an oscillating instead of a revolving magnet is employed, is shown in figs. 4 and 5, and is intended to be used in connection with the well-known "dry" gas-meter. In this case the vertical spindle E, which is operated by the usual mechanism within the meter, has at its upper end, within a packed casing, k, an arm, q, adapted to the teeth of a wheel, L, which is by this means slowly

turned to the extent of one tooth at every revolution of the spindle. An arm, *r*, is secured to the spindle of the wheel *L*, and is so placed that when the latter revolves, the arm will strike and alternately move the opposite poles of a horse-shoe magnet *G*, which is arranged to oscillate freely upon suitable trunnions within the casing *k*. This oscillating motion of the magnet is communicated, through a copper plate, *s*, to an oscillating-bar, *J*, and thence to any suitable system of registering-wheels, as in the previous cases. In all these instances the magnet should be protected against corrosion from the fluid to be measured, by coating it with silver, gutta percha, or with any non-conducting, insoluble varnish. It may sometimes be preferable to keep the magnet in constant contact with a soft-iron armature, in order to insure its stability; and the armature may consist of a series of anti-friction rollers, that will facilitate the motions of the magnet. The box or casing in which the magnet is contained may consist of any suitable metal, but where iron or steel, or other conducting metal is employed, I prefer to coat the inside of the box with some non-conducting substance that will not interfere with the proper motions of the magnet.

It will be evident, from the above description, that by slightly modifying the form and arrangement of my invention, it can be applied to any fluid-meter in use, and when so applied, the usual complicated registering-devices can be dispensed with, thus reducing the expense and adding to the accuracy of the meter.

Without, therefore, confining myself to any specific construction or arrangement of parts, I claim as my invention, and desire to secure by Letters Patent—

The combination, substantially as described, of a revolving or oscillating magnet and the registering-bar *J*, or its equivalent, with a fluid-meter, for the purpose specified.

In testimony whereof, I have signed my name to this specification in the presence of two subscribing witnesses.

CHAS. STEIN.
